UNITED STATES PATENT OFFICE.

FRED C. HAMMOND, OF SPRINGFIELD, VERMONT, ASSIGNOR OF ONE-HALF TO
WILLIAM L. WHITCOMB, OF SAME PLACE.

BEAM-SCALES.

SPECIFICATION forming part of Letters Patent No. 416,261, dated December 3, 1889.

Application filed July 18, 1889. Serial No. 317,856. (No model.)

To all whom it may concern:

Be it known that I, FRED C. HAMMOND, of 5 Springfield, county of Windsor and State of Vermont, have invented a certain new and useful Improvement in Beam-Scales, of which I declare the following to be a full, clear, and exact description, reference being had to the accompanying sheet of drawings, forming part of this specification.

10 This invention relates to improvements in weighing-scales, such as are commonly termed "beam-scales," which are made to balance by means of a poise that is moved back and forth along the beam; and the invention consists 15 of a beam - scale provided with a poise, and mechanism whereby the same is actuated, and of a recording attachment to be used in connection therewith, constructed and operating substantially in the manner and for the purpose herein described and claimed.

20 In the accompanying drawings, Figure 1 is a side elevation of the invention, partly in section; Fig. 2, a cross-section in the plane 2 2, Fig. 1; Fig. 3, a cross-section in the planes 3 3, Fig. 1; Fig. 4, a detail of one of the standards of the recording-roller.

25 Similar letters of reference indicate like parts in the several views.

The object of this invention is to render a 30 platform-scale, a grocer's counter-scale, or any other similar beam-scale automatic with respect to the balancing of the beam by the poise and the indicating or recording of the weight. This object is effected by means of 35 a rolling poise in connection with a sliding index.

The drawings represent the upper portion of a platform-scale, and the invention is herein described as applied to such a scale; but 40 these drawings, with the description, will enable the invention to be thoroughly understood, so that it can also be readily embodied in beam-scales of other forms.

The beam, poise, and index are designated, 45 respectively, by A, B, and C. The poise is round and is mounted on the beam, being kept in place by the groove a, in which the edge of the beam is received, and from each face of the poise projects a small pin b, which 50 is coincident with the axis of the poise.

The beam is not graduated or notched along its upper edge, as such beams usually are, and it is hung in such a manner that the straight portion of its upper edge passes above and below the horizontal plane Z Z as the outer 55 end of the beam is elevated and depressed, thus causing the edge when in one position to incline toward the standard and in the opposite direction when in the other position. The index rests and slides freely upon a bar 60 c, and its lower portion extends downward in two branches or limbs d d, which stand on opposite sides of the poise, as shown in Fig 2, when this passes beneath the index, and with which the pin b of the poise either comes in 65 contact or under which it passes, according to the position of the beam. The pointer e of the index projects up through a slot f in the ordinary arm D of the scale - frame, and behind the pointer is fixed a graduated plate 70 E. The bar c is supported by the frame, to which it may be attached in any convenient manner. It has near its inner end a curved shoulder c'.

To the bracket F, near the outer end of the 75 arm D, is secured a slide G, through which, as well as through the bracket F, the beam passes. This slide has a vertical movement, and is held in place by a suitable guide. A latch g supports it in its highest position, 80 while a spring h tends to push it downward. The bar c and plate E are inclined slightly away from the standard of the scale for reasons that will hereinafter appear.

The operation of that portion of the invention which has been described may here be explained. The parts of the scale being in the respective positions in which they appear in Fig. 1, and the article to be weighed being placed upon the scale, the outer end of the 90 beam is thrown upward and the latch g is thereby tripped, so that the spring h pushes the slide G against the beam. The power of the spring is such that in case the weight upon the scale is not greater than the highest 95 number of pounds indicated on the graduated plate E, then the outer end of the beam will at once be forced downward by the slide; but in case the weight is greater than the number of pounds thus indicated a weight or 100

weights of the ordinary kind should be added at the outer end of the beam until the resistance thereof to the spring becomes somewhat less than the power of the spring, whereupon the spring's action will be the same as in the former case. The end of the beam is thus depressed to such an extent that the edge on which the poise travels is inclined away from the standard; but the beam is not forced by the slide down to the bottom of the opening in the bracket F. This inclination of the beam causes the poise to roll forward, and in so doing it pushes before it the index C. When the poise reaches the proper point, the beam balances, its outer end falls as far as the bracket F will allow it to go, and the index is left at that point by the poise, which drops, so that the pin b passes under the limbs d d and the poise rolls on until it meets the bracket F. The index then marks on the plate E the weight of the article on the scale or the excess of its weight over the amount represented by the weight or weights at the end of the beam. Upon the end of the beam being lifted with the hand this will again be held up by the latch, and the inclination being reversed the poise will roll toward the standard, and when it reaches the index this will be carried along by it, since the poise will then have been raised far enough to allow the pin b to once more strike the limbs d d of the index. This will be carried back in the manner described to the curved shoulder c', and here the momentum of the poise will tip the index and force it up on the shoulder, so that the pin b will pass under the limbs d d, and then the index will fall back, guided by the curved surface of the shoulder, into its proper position on the bar c.

Provision is made for obtaining a certain number of pounds of a commodity—as, for instance, grain or coal—in the following manner: A bar H is pivoted to links h' and h'', each of which is also pivoted to some stationary portion of the scale, as the arm D, a suitable handle being fixed to the link h' and the bar H being so located that it shall press against the index C when the links are vertical and hold it fast upon the bar c, as will be understood by reference to Fig. 2. The index now being set to indicate the weight desired, either with or without any number of weights at the outer end of the beam, it is clamped at that point by moving the handle of the link h', and a convenient quantity of the substance to be weighed is placed on the scale. The end of the beam is first thrown up and then forced down by the slide G, as before explained, and the poise rolls forward to the index. The link h' is arranged to serve as a stop to limit the descent of the slide G, so that the beam shall not be allowed to fall quite far enough to enable the poise to roll beyond the index, though the beam may fall somewhat below the position to which the spring h depresses it. Thus the quantity of the substance on the scale may be increased

or decreased until the beam is caused to balance, the same as in the case of an ordinary scale, the poise remaining constantly at the index, since the direction of the inclination of the beam does not change so as to affect the poise after the first downward motion of the slide.

The recording attachment now remains to be described. On the arm D a roller H', covered with paper, is mounted in standards i i', and the index C is provided with a needle k, which extends upward close to the under surface of the roller. A pawl l, fastened to the arm, engages with a ratchet-wheel m at the end of the roller, and to the end of the roller-shaft is pivoted a bar n, which passes down near the end of the beam and has at its lower end a projection o. The standard i' is slotted, as appears by Fig. 4, and the bar n has a notch p in its edge, into which enters a plate, (shown in Fig. 1,) at the end of the spring h, and is so weighted at its lower end that this naturally rests close to the end of the scale-beam, and when the shaft is lifted in the slotted standard i' to the upper end of the slot the notch p is caused by the gravity of the bar n to engage with the plate on the arm and hold the roller in that position. The roller H' being thus elevated, when the outer end of the beam descends under the weight of the poise, as in the operation of the scale above described, the beam strikes the projection o of the bar n, thus forcing the notch p off the supporting-plate, and the roller H' falls on the needle of the index, which pierces the paper surface of the roller, and thus marks the weight upon it. The roller is returned to its elevated position by the slide G acting against the shaft, when the outer end of the beam is lifted by the hand, and it is at the same time turned slightly on its axis by the pawl-and-ratchet wheel l and m, so that a fresh portion of the surface shall each time be presented to the needle, thus enabling a large number of weights to be recorded upon a single roller. The weights are read from the roller by the graduations of the scale E.

Having now described my invention, what I claim as new, and desire to secure by Letters Patent, is—

1. The combination of the beam, the rolling poise mounted on the beam, and the sliding index actuated by the poise, substantially as and for the purpose described.

2. The combination of the beam, a support and stop to regulate the inclination thereof, the rolling poise mounted on the beam, and the sliding index separate from but actuated by the poise, as and for the purpose described.

3. The combination of the beam, the slide G, forming a support and stop to regulate the inclination of the beam, the rolling poise mounted on the beam, and the sliding index actuated by the poise, as and for the purpose described.

4. The combination of the beam, a support and stop to regulate the inclination thereof,

the rolling poise mounted on the beam and provided with the axial pin *b*, and the sliding index having the depending limbs *d d'*, constructed and operating as described.

5 5. The combination of the beam, a support and stop to regulate the inclination thereof, the rolling poise mounted on the beam, the inclined bar *c*, having the shoulder *c'*, and the sliding index mounted on the bar *c*, as and 10 for the purpose described.

6. The combination, in a beam-scale, of a 15 rolling poise and separate index, the index being actuated by the poise when the beam of the scale is inclined to some extent, and being left by the poise when the beam is depressed to a sufficient extent, substantially in the manner and for the purpose described.

7. The combination of the beam, a support and stop to regulate the inclination thereof, 20 the rolling poise mounted on the beam, the sliding index coacting with the poise, and a holding device to fix the index at different points along its course, substantially as and for the purpose described.

25 8. The combination of the beam, the slide *G*, to regulate the inclination thereof, the poise *B*, mounted on the beam, the bar *c*, the

index *C*, mounted thereon, the clamping-bar *H*, and the link *h'*, which supports the bar *H* and serves as a stop to limit the descent of 30 the slide *G*, substantially as and for the purpose described.

9. The combination of the index provided with the needle *h*, projecting upward above the beam, the roller *H'*, mounted above the 35 index and having a vertical movement, the bar *n*, supporting the roller in an elevated position and extending downward therefrom to the level of the beam, and the beam, whereby the bar *n* is moved to allow the roller to 40 fall upon the needle of the index, substantially as described.

10. The combination of the index, the roller *H'*, having a vertical movement, the pawl and ratchet-wheel *l* and *m*, the bar *n*, and the 45 beam *A*, as and for the purpose described.

11. The combination of the index, the roller *H'*, the bar *n*, the beam acting on the bar, and the slide *G*, whereby the roller is elevated, as and for the purpose described.

FRED C. HAMMOND.
